US0D1011891S

(12) **United States Design Patent** (10) **Patent No.:** **US D1,011,891 S**
(45) **Date of Patent:** **** Jan. 23, 2024**

(54) **BOTTLE**

- (71) Applicant: **PepsiCo, Inc.**, Purchase, NY (US)
(72) Inventors: **William R. Eaton**, Southbury, CT (US); **Christopher Andrew Gregory**, New York, NY (US); **Niklas Gustafsson**, New York, NY (US); **Stephen Lim**, Chappaqua, NY (US); **Kai Xiang Lin**, Flushing, NY (US); **Christopher Nobles**, Brooklyn, NY (US); **Qiuchen Peter Zhang**, Mahwah, NJ (US)
(73) Assignee: **PepsiCo, Inc.**, Purchase, NY (US)
(**) Term: **15 Years**
(21) Appl. No.: **29/865,157**
(22) Filed: **Jul. 11, 2022**

Related U.S. Application Data

- (63) Continuation of application No. 29/707,640, filed on Sep. 30, 2019, now Pat. No. Des. 958,662.

(57) **CLAIM**

The ornamental design for a bottle, as shown and described.

DESCRIPTION

FIG. 1 is a top perspective view of a bottle showing the claimed design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top perspective view of another embodiment thereof;

FIG. 10 is a bottom perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof; and,

FIG. 16 is a bottom view thereof.

The dashed broken lines in the figures show portions of the bottle that form no part of the claimed design.

The dot-dash broken lines in the figures show boundaries that form no part of the claimed design.

1 Claim, 14 Drawing Sheets
